METER FOR MEASURING THE DECELERATION OF VEHICLES

Paul Vogt, Les Hauts-Geneveys, Neuchatel, Switzerland,
assignor to Ebauches S.A., Neuchatel, Switzerland

Filed Aug. 1, 1962, Ser. No. 71,129

Claims priority, application Switzerland, Feb. 3, 1962,
98,226/62

Term of patent 14 years

(Cl. D52—6)

FIG.1

FIG.2

FIG. 1 is a perspective view from the top, side and front of a meter for measuring the deceleration of vehicles, embodying my new design.

FIG. 2 is a perspective view as viewed from the rear and bottom thereof.

The undisclosed side of the meter is substantially the same in appearance as the side shown.

I claim:

The ornamental design for a meter for measuring the deceleration of vehicles, substantially as shown and described.
